UNITED STATES PATENT OFFICE.

NATHAN W. FLETCHER, OF CHICAGO HEIGHTS, ILLINOIS, ASSIGNOR TO
TURBINE MOTOR TOOL COMPANY, OF CHICAGO, ILLINOIS, A CORPO-
RATION OF ILLINOIS.

PNEUMATIC TOOL.

No. 833,710.

Specification of Letters Patent.

Patented Oct. 16, 1906.

Application filed May 20, 1904. Serial No. 208,981.

To all whom it may concern:

Be it known that I, NATHAN W. FLETCHER, a citizen of the United States, and a resident of Chicago Heights, in the county of Cook and State of Illinois, have invented certain new and useful Improvements in Pneumatic Tools, (Case B;) and I do hereby declare that the following is a full, clear, and exact description thereof, reference being had to the accompanying drawings, and to the letters of reference marked thereon, which form a part of this specification.

This invention relates to implements for polishing or grinding of that class embracing a rotative or turbine motor operated by air or other gaseous fluid and which operates a rotative grinding or polishing tool.

The implement embodying my invention is more especially designed for use in connection with a planing-machine, lathe, or like machine by which bodily motion may be given to the machine, to the work, or to both.

The invention consists in the matters hereinafter set forth, and pointed out in the appended claims.

As shown in the drawings, Figure 1 is a view in side elevation of an implement embodying my invention. Fig. 2 is a plan view of the implement as applied to the tool-support of a lathe in position to operate upon a cylindric blank which is actuated by the lathe. Fig. 3 is a sectional view taken upon line 3 3 of Fig. 2. Fig. 4 is a plan section taken on line 4 4 of Fig. 1. Fig. 5 is a detail section of the parts which support the motor, with the motor omitted, taken upon line 5 5 of Fig. 1. Fig. 6 is a detail section taken on line 6 6 of Fig. 1. Fig. 7 is a perspective view showing the tool embodying my invention secured to the tool-holder of a lathe and arranged to operate upon the interior of a tube held in a lathe-chuck. Fig. 8 is a sectional plan view of the base-plate of the implement when arranged for operation as shown in Fig. 7. Fig. 9 is a detail section taken upon line 9 9 of Fig. 8. Fig. 10 is a view in side elevation of the implement shown in the preceding figures as applied to the reciprocating head of a planing-machine or shaper.

As illustrated in said drawings, A indicates the non-rotative member of a turbine or

other rotative motor, and A' an annular casing or housing which forms part of said non-rotative member A and incloses the rotative member of the motor, the central part of which is indicated by B.

B' indicates a belt-pulley which is attached to the rotative member of the motor and which projects through the central aperture in one side of the case or inclosure A'.

C indicates a shaft on which the rotative part of the motor turns.

D indicates a base-plate having at its opposite sides two standards D' D'', between which the motor is located and at the upper ends of which are formed bearings d d', in which the ends of the motor-shaft C are rigidly secured. The non-rotative part A of the motor is rigidly secured to the said shaft C. Said casing or housing A', which surrounds the rotative member of the motor, is provided in its side wall adjacent to the belt-pulley B with a central opening (shown in Figs. 1 and 2) through which the belt-pulley 75 extends. The non-rotative part A of the motor is provided with a tubular handle A'', to the outer end of which is connected the air-supply pipe A' and through which air under pressure is conveyed to the non-rotative 80 member of the motor. The casing A' is provided with an exhaust-outlet A''. The said base-plate D is attached to the top surface of a supporting-plate E, provided at one end with two alined bearings e e' for a tool-spindle 85 and at its opposite end with like alined bearings e'' e''' for another tool-spindle. At its central part said plate E is provided in its top surface with a transverse concave depression e'' and on its lower surface with a trans- 90 verse convex projection e'', giving to the central part E' of the plate the form of a cylindric segment. In said central segmental part E' is formed a longitudinal slot E'', Fig. 4.

F is a saddle-block having a concave top bearing-surface f, adapted to receive the convex projection e'' at the center part of the supporting-plate. In the concave depression e'' rests a block G, curved at its lower surface to fit said depression. Said blocks F 100 and G are centrally apertured for the passage of a clamping-bolt H, by which the device as a whole may be attached to the tool-support of a lathe or other machine. Said clamping-bolt is

shown as having at its lower end, below the block F, a head H' and having at its upper end a nut h, provided with radial holes for engagement with a spanner or like tool. Figs. 1 and 3 illustrate the operation of these parts in attaching the implement to the tool-support I of a lathe. Said tool-support I is provided with a T-shaped or undercut slot i, which opens upwardly through the top surface thereof and is adapted to receive the head H' on the holding-bolt H. When the head of the bolt is inserted in the slot i and the clamping-bolt tightened by turning the nut h, the supporting-plate E will be rigidly clamped to the tool-support. The angle of the said plate E with respect to a horizontal plane may be changed by shifting or sliding the segmental part E' endwise between the blocks F and G before the clamp-bolt is tightened to secure the parts from movement.

As shown in Figs. 1 to 6, inclusive, a tool-spindle N is mounted in the bearings e e' on one end of the supporting-plate E. Said spindle is provided between said bearings e e' with a belt-pulley n, over which and the pulley B of the motor is trained a driving-belt B². Said tool-spindle also has attached to its end which projects from one side of the plate E a grinding-disk N'.

As shown in Figs. 2, 3, and 7, I have shown parts of a lathe of ordinary construction wherein the tool-holder I is mounted to slide endwise on a plate I', which is connected by a vertical pivot with a slide J, adapted to slide transversely of the lathe-bed on a tool-carriage J', the tool-support I being thus adapted to rotate in a horizontal plane, but means being used, of familiar construction, to clamp said tool-holder rigidly in any position in which it may be placed. Said slide J is mounted on transverse guides j j, attached to the tool-carriage J', which latter is mounted on the longitudinal guides j' j' on the lathe-bed and adapted to be moved endwise thereon by means of a gear-pinion J² on the carriage, adapted to engage a rack j² on the bed. In said Figs. 2, 3, and 7 K indicates the head-stock, K' the tail-stock of the lathe, and L indicates a chuck attached to the live-spindle. Said figures illustrate the tool embodying my invention when applied to grind a cylindric blank, (indicated by M,) which is held by the chuck L at one end and engaged at its opposite end by the center k' on the tail-stock K'. When the tool is thus mounted on the tool-carriage J of the lathe, the grinding-wheel N' may be adjusted in proper position for action on the blank M. Said carriage may be moved so as to carry the grinding-wheel endwise of the blank while the latter is being rotated by the lathe and the entire exterior surface of the blank thereby ground to a true cylindric shape. The 65 grinding-disk will be adjusted to make a

lighter or heavier cut by moving the tool-support I inwardly or outwardly in the manner usual when working with cutting-tools.

Fig. 6 is a sectional view through the bearings e e' for the tool-spindle N. The said bearings are provided in their external end faces with conical depressions forming outwardly-facing conical bearing-recesses, and the said spindle N at its end to which the tool is attached is provided with a flange or enlargement n', having a conical bearing-face adapted to engage the conical bearing-recess in the adjacent bearing e'. At the opposite end of said spindle the same is screw-threaded and provided with a nut n², having its inner face made conical to fit the conical bearing-recess in the bearing e.

In Fig. 3 I have shown the exhaust-nozzle A⁴ on the motor-casing A' as provided with a tubular extension A⁵, which is bent or deflected downwardly, so that its open end is directed toward the blank M at a point where the grinding-disk operates upon the same. By the use of such tubular extension A⁴ of the exhaust-nozzle the exhaust-air as it passes from the motor is directed downwardly against the blank and serves to remove or carry away the dust or cuttings as fast as the same are formed.

Figs. 7, 8, and 9 illustrate an implement embodying my invention as applied to grinding the interior of a sleeve or other hollow object. For doing work of this kind I place in the bearings e² e³ of the plate E a tool-spindle O, provided between said bearings with a belt-pulley O', adapted to receive motion from the pulley B' on the motor through a driving-belt B². Said shaft O extends laterally from the side of the plate E and has on its extremity a grinding-disk O² of a size smaller than the internal diameter of the sleeve or other object to be ground. To provide a rigid support for the outer end of the shaft O, or that adjacent to the grinding-disk O², I provide the plate E with a bearing-sleeve P, which is secured in the bearing e² and through which the shaft O extends. Said sleeve is provided at its outer end with an annular bearing-surface p for engagement with a corresponding conical bearing-surface o on an enlargement o' of said shaft O. Said sleeve is also provided near its inner end with bushings p' p², forming bearings for the central part of the shaft O. In order to rigidly secure the bearing-sleeve P in the bearing e², the latter is longitudinally split or severed and provided with lugs e⁶ e⁷ at opposite sides of the slit between its separated parts, through which lugs are inserted clamping screws or bolts e⁸ e⁹. The said sleeve P fits closely within the cylindric bearing-aperture of the bearing e² and is rigidly secured therein by the tightening of the screws e⁸ e⁹. Said sleeve P is, moreover, preferably extended inwardly past the inner face of the bearing e² 130

to the adjacent side face of the pulley O'. The inner end of said shaft O is shown as fitting and turning within an aperture formed in the bearing e¹, the shaft having on its end exterior to the bearing e¹ a collar o' and a nut o'.

When the tool provided with the grinding-disk O' for internal grinding is applied to a lathe, the parts may be arranged as shown in Fig. 7, said supporting-plate E being reversed or placed end to end as compared with its position as shown in Figs. 2 and 3, so as to bring the end of the tool-spindle O bearing the grinding-disk toward the work held in the chuck L. M' in said Fig. 7 indicates a tubular blank held in the said chuck L with its open end presented toward the tool. In adjusting the grinding-disk O' with respect to the work the spindle O may be raised or lowered by swinging the central curved part of the plate E in the saddle-block F. Movement of the said grinding-disk toward the surface being ground is effected by shifting the tool-carrier I inwardly or outwardly in the usual manner. For grinding conical or tapered objects on a lathe or for use as a center grinder for lathes the implement described will be mounted on the tool-support I with the plate E transverse to the side face of said tool-support, or at right angles to its position in Figs. 2 and 3. When thus mounted, the tool-support is fixed at an angle corresponding to the angle of the conical surface to be ground, while the tool-spindle N will be parallel with said surface. The supporting-plate E may then be moved laterally by the endwise shifting of the tool-support, so as to carry the grinding-disk along the conical surface.

In Fig. 10 a tool embodying my invention is shown as applied to that form of a planing-machine known as a "shaper" for the purpose of grinding a flat surface. In this instance Q indicates the horizontally-reciprocating head of a shaping-machine on which is mounted a vertically-adjustable tool-holder Q'. Said tool-holder is adapted for engagement with the head of the holding-bolt H, by which the saddle-block F and the plate E may be clamped to said tool-holder Q' in the same manner as hereinbefore described. In this instance, however, the supporting-plate E is arranged vertically, with the grinding-wheel N' below the tool-holder. R indicates a work-supporting table, which is adapted to slide laterally to bring different parts of the work successively under the action of the tool when the latter is moved horizontally with the reciprocating head Q. A work-holder R' is shown as attached to the upper surface of the table R, and a blank having the form of a flat plate S is shown as secured in said work-holder. In the operation of this device the forward and backward horizontal movement of the head Q moves the tool bodily over or across the

blank S, and said blank will be shifted side-wise or laterally to bring the different parts of the surface successively under the action of the grinding-disk by shifting the table R sidewise through the use of the devices 70 usually employed in such machines for this purpose. I have shown the base-plate D, on which the motor is directly mounted, as being provided at one end with lugs or standards D² D³, adapted to form bearings for a 75 tool-shaft. Such bearings will be useful in cases where the base plate D, with the turbine, is detached from the supporting-plate E, as may sometimes be done in cases in which said plate E may be conveniently attached directly to some part of a machine. While the main frame of the tool illustrated is formed by means of the supporting-plate E and the separate plate D, to which the motor is directly secured, yet this particular 80 construction in said frame is not essential, and said frame may be otherwise constructed in a manner to properly support the motor and to provide for its adjustable attachment to a lathe or other machine in connection 85 with which the machine is used.

I claim as my invention—

1. The combination of a supporting-plate provided between its ends with a curved portion having opposite, parallel, concave and 90 convex surfaces, a base-plate attached to the upper surface of said supporting-plate, a motor mounted on said base-plate, a tool-spindle mounted in said supporting-plate, driving means connecting the rotative member of the motor with said tool-spindle, a saddle-block having a concave surface adapted to fit the convex surface of said supporting-plate, and a clamping-bolt inserted through the curved portion of the supporting-plate 95 and through said saddle-block.

2. The combination of a supporting-plate provided between its ends with a curved portion having opposite, parallel, concave and convex surfaces, a base-plate attached to the upper surface of said supporting-plate, a motor mounted on said base-plate, a tool-spindle mounted in said supporting-plate, driving means connecting the rotative member of the motor with said tool-spindle, a saddle-block having an upwardly-facing concave surface fitting the convex surface of said supporting-plate, a block having a convex lower surface and fitting within the concave surface of said supporting-plate, and a clamping bolt inserted through said block, through the curved portion of the supporting-plate and 110 through said saddle-block.

3. The combination of a supporting-plate having bearings at its opposite ends for tool-shafts and provided between its ends with a curved portion having opposite parallel, concave and convex surfaces, a base-plate attached to the upper surface of said supporting-plate, a motor mounted on said base- 115

plate, a saddle-block having a concave surface adapted to fit the convex surface of said supporting-plate, and a clamping-bolt inserted through said curved portion of the supporting-plate and through said saddle-block.

4. The combination with a lathe or other power-driven machine, of an attachment embracing a rotative tool, a motor, a supporting-plate provided with a bearing for said tool and having between its ends a curved portion provided with opposite parallel concave and convex surfaces, a base-plate attached to the upper surface of said supporting-plate and on

which the said motor is mounted, a saddle-block having a concave surface adapted to fit the convex surface of the said supporting-plate, and a clamping-bolt inserted through the said curved portion of the supporting-plate and through said saddle-block.

In testimony that I claim the foregoing as my invention I affix my signature, in presence of two witnesses, this 13th day of May, A. D. 1904.

NATHAN W. FLETCHER.
